BLASTING CARTRIDGE

Wade H. Wineman, Michigan City, Ind., assignor,
by mesne assignments, to Safety Mining Com-
pany, Chicago, Ill., a corporation of Illinois

Application June 5, 1934, Serial No. 729,110

20 Claims. (Cl. 102—6)

This invention relates to blasting cartridges, and more particularly to improvements in a cartridge of the type in which highly compressed gas is used as a blasting medium.

An object of this invention is to provide an improved blasting cartridge of the compressed gas type and having improved means for suddenly releasing the pressure when a predetermined blasting pressure is attained. Another object is to provide an improved blasting cartridge having improved valve mechanism and having associated therewith improved means for effecting quick opening of the valve mechanism to release suddenly the pressure when a predetermined blasting pressure is attained within the cartridge casing. These and other objects of the invention will, however, hereinafter more fully appear.

In the accompanying drawing there are shown for purposes of illustration several forms which the invention may assume in practice.

In this drawing,—

Fig. 1 is a central, longitudinally extending, sectional view through the improved blasting cartridge construction in accordance with one illustrative form of the invention.

Fig. 2 is a view similar to Fig. 1 showing the parts in pressure releasing position.

Fig. 3 is a view similar to Fig. 1, showing a modified form of construction.

Fig. 4 is a fragmentary view similar to Fig. 2 showing the valve in pressure releasing position.

Fig. 5 is a cross sectional view taken on line 5—5 of Fig. 4.

Fig. 6 is similar to Fig. 3 showing a still further modified form of construction.

In the illustrative form of the invention shown in Figs. 1 and 2 there is shown a blasting cartridge of the type in which highly compressed gas is used as a blasting medium, and comprising a cylindrical metallic casing or shell 1 having a chamber 2 which is adapted to contain a charge of gas compressed to a high pressure. The outer end of this casing is closed by a head 3 threaded to the casing at 4 and locked in position by a wire spring lock 5 of a known design, and comprising a wire bent to a suitable form and having end portions projecting within notches cut in the adjacent ends of the casing and head.

As illustrated, the head 3 is provided with a central bore 6 to which there is conducted a highly compressed gas through a tube connection 7 threaded within the head wall 8. Threaded at 9 within the opposite or inner end of the casing 5 is a hollow cap 10 perforated with discharge holes

11 extending from its central recess 12 to the exterior. Connecting the pressure chamber 2 with the central recess of the cap 10 is an axial passage surrounded by a conical valve seat 13 with which engages the conical valve portion 14 of a pressure release valve 15. The wall of this valve seat 13 is annularly grooved at 16 to receive an annular ring 17 preferably composed of rubber and engageable with the valve portion 14 in the sealing of the valve on its seat. Threadedly connected at 18 to the valve 15 is an axial rod 19 extending centrally through the chamber 2 and projecting within the chamber 6 within the rear head 3. Reciprocably mounted within the bore 6 is a piston 20 having an axial opening 21 through which the rod 19 extends and carrying a cup packing 22 for preventing leakage of compressed gas from the chamber 2 into the bore 6 past the piston and rod. This packing is held in position by a cap retaining plate 23 secured to the piston by screws 24, and inward movement of the piston 20 is limited by stop lugs 25 secured to the rod 19. Interposed between the piston and a collar 26 secured to the outer end of the rod and encircling the rod is a coil spring 27.

Highly compressed gas, herein compressed air under high pressure, is conducted through the tube 7 to the bore 6 in the head, through the bore and past the piston 20 exteriorly of the packing 22 to the pressure chamber 2. When a predetermined blasting pressure is attained within the chamber 2 the supply of compressed gas through the tube 7 is cut off in any suitable manner and the bore 6 at the outer side of the piston connected to atmosphere through any suitable vent means under the control of the operator so that the pressure in the bore 6 is reduced thereby reducing the pressure acting on the rear area of the piston 20. The relatively high pressure within the chamber 2 acting on the inner pressure area of the piston causes the piston to move outwardly relative to the rod 19 while at the same time the spring is increasingly compressed. When the spring becomes compressed to a certain degree the same effects sudden outward movement of the rod 19 and the valve 16 is quickly unseated thereby permitting a sudden release of the compressed gas from the chamber 2 through the chamber 12 and discharge holes 11 in the cap 10 and as a result effecting breaking down of the material to be blasted.

In the modified form of construction shown in Figs. 3 to 5 inclusive, there is shown a cylindrical casing or shell 30 having a pressure receiving chamber 31 and communicating with this cham-

ber is a bore 32 closed at the outer end of the cartridge by a head member 33. Threadedly connected at 34 to the inner end of the shell is a hollow cap 35 perforated with discharge holes 36 extending from its central recess 37 to the exterior. Connecting the inner end of the pressure chamber 31 with the recess 37 in the cap is an axial opening 38 surrounded by a conical valve seat 39 with which the conical valve portion 40 of a pressure release valve 41 engages. As in the form of the invention shown in Figs. 1 and 2, this valve seat is annularly grooved at 42 to receive a rubber sealing ring 43. Reciprocable in the bore 32 is a piston 44 carrying a cup packing 45 for permitting flow of compressed gas from the bore 32 to the pressure chamber 31 but preventing leakage of pressure from the pressure chamber. Threadedly engaged with the piston 44 is a rod 46 herein formed integral with the valve 41, and threadedly engaged with this rod is a nut 47 engaging a washer 48 for holding the cup packing 45 on the piston. In this instance formed in the piston is a valve chamber 49 having a valve seat 50 with which a ball valve 51 engages. This valve controls the communication of the valve chamber 49 with the bore 32 through a passage 52. A passage 53 formed in the rod 46 connects the valve chamber 49 with the pressure chamber 31. Connected to the head 33 is a pipe connection 54 for supplying highly compressed gas through a passage 55 to the bore 32 at the outer side of the piston 44, and for venting bore 32 when desired.

From the foregoing it will be evident that when compressed gas, herein air under high pressure, is supplied through the pipe connection 54 and passage 55 to the bore 32, the compressed gas will flow from the bore 32 through passage 52 past the ball valve 51 which is at that time off its seat, 40 and through passage 53 to the valve 51. Pressure fluid will also flow past the cup packing 45 to the pressure chamber 31. When the desired blasting pressure is attained within the pressure chamber 31, the supply of compressed gas to the pipe connection 54 is cut off and this pipe connection 45 suitably connected to atmosphere. This will cause the ball valve 51 to close the passage 52 and the relatively high pressure in the chamber 31 will move the piston 44 outwardly thereby 50 to move the valve 41 into its unseated position shown in Fig. 4, and as a result the pressure in the chamber 31 is suddenly released through the axial recess 37 in the cap and discharge holes 36.

55 In the modified form of construction shown in Fig. 6 the cartridge shell, pressure chamber, bore 32, outer head 33, the cap 35 and the valve 41 are similar to those disclosed in the form of invention shown in Figs. 2 to 5 inclusive. In this 60 form of the invention, however, the piston structure for operating the valve 41 and the means for supplying compressed gas to the pressure chamber 31 are somewhat modified. In this instance, the rod 60, with which the valve 41 is integrally formed, has a shoulder 61 with which it 65 engages an annular plate 62 forming the piston head. Threadedly secured at 63 to the outer end of the rod 60 is a nut 64 for holding a cup packing 65 in position on the piston head and 70 the piston head in engagement with the shoulder 61. The piston 62 is annularly grooved at 66 to receive a radially expansible ring 67. This ring moves the cup packing into tight frictional engagement with the wall of the bore 32. In this 75 instance, the valve 41 is provided with a cylindri-

cal portion 68 adapted to fit in the axial bore 38 when the conical portion of the valve is on the seat 39 thereby to provide a tighter seal between the pressure chamber and the cap discharge recess 37. Otherwise this form of the invention is 5 similar to that shown in Figs. 3 to 5 inclusive.

When compressed gas is supplied through the pipe 54 and passage 55 to the bore 32 the compressed gas flows from the bore 32 past the cup packing 65 to the pressure chamber 31. When the 10 desired blasting pressure is attained within the pressure chamber 31 the supply of compressed gas in the pipe connection 54 is cut off and the latter suitably vented to atmosphere. The sudden drop in pressure in the bore 32 causes the pressure 15 in the chamber 31 to move the piston 62 rearwardly thereby to unseat the valve 31 and to release suddenly the blasting pressure from the chamber 31.

As a result of this invention it will be noted that 20 an improved blasting cartridge is provided of the type in which highly compressed gas is used as a blasting medium, having improved and simplified means for suddenly releasing the blasting pressure from the pressure chamber when a predetermined pressure is attained within the cartridge casing. It will further be noted that an improved blasting cartridge is provided having improved pressure releasing valve mechanism and improved and simplified means for supplying compressed gas to the pressure chamber and for actuating the valve mechanism to effect sudden release of the blasting pressure. These and other uses and advantages of the improved blasting cartridge will be clearly apparent to those skilled 35 in the art.

While I have in this application specifically described several forms which my invention may assume in practice, it will be understood that these forms of the same are shown for purposes 40 of illustration, and that the invention may be further modified and embodied in various other forms without departing from its spirit or the scope of the appended claims.

What I claim as new and desire to secure by 45 Letters Patent is:—

1. In a blasting cartridge, a casing having a chamber for receiving a blasting charge, a valve for releasing the pressure from said chamber, and a piston actuated by the pressure in said chamber 50 for actuating said valve, said piston having a packing serving as a check valve for the pressure supplied to said chamber.

2. In a blasting cartridge, a casing having a chamber for receiving a blasting charge, a valve 55 for releasing the pressure from said chamber, a piston actuated by the pressure in said chamber for actuating said valve, and a compressible connection between said piston and said valve for permitting relative movement of said valve and 60 piston.

3. In a blasting cartridge, a casing having a chamber for receiving a charge of blasting pressure, a valve for releasing said pressure from said chamber, and means controlled by the pressure in 65 said chamber for actuating said valve comprising a rod, a piston and a yielding connection between said piston and rod.

4. In a blasting cartridge, a casing having a chamber for receiving a charge of blasting pressure, a valve for releasing the pressure from said chamber, a piston secured to the valve and controlled by the pressure in said chamber for moving said valve, and means carried by the periphery of said piston for controlling the flow of com- 75

pressed gas to said pressure chamber in one direction but preventing leakage from the chamber in the opposite direction.

5. In a blasting cartridge, a casing having a chamber for receiving a charge of blasting pressure, a valve for releasing the pressure from said chamber, a piston secured to said valve and controlled by the pressure in said chamber for actuating said valve, and combined valve and packing means carried by said piston in radially spaced relation to the axis thereof for controlling the supply of pressure fluid to said pressure chamber.

6. In a blasting cartridge, a casing having a chamber for receiving a charge of blasting pressure, a valve for releasing said pressure from said chamber, a piston secured to said valve and controlled by the pressure in said chamber for actuating said valve, and a cup packing carried by said piston for permitting pressure fluid to flow to said chamber but preventing leakage of pressure fluid from said chamber.

7. In a blasting cartridge, a casing having a chamber for receiving a charge of blasting pressure, a valve for releasing said pressure from said chamber, a piston secured to said valve and controlled by the pressure in said chamber for actuating said valve, a cup packing carried by said piston for permitting pressure fluid to flow to said chamber but preventing leakage of pressure fluid from said chamber, and an expansible means carried by said piston for holding said cup packing in tight engagement with the wall of the bore within which said piston moves.

8. In a blasting cartridge a casing having a chamber for receiving a charge of blasting pressure, a valve controlled by the pressure in said chamber and movable inwardly for releasing the pressure from said chamber, a valve seat facing inwardly toward said chamber and with which said valve engages, an annular groove formed in the walls of said seat, and a rubber ring mounted in said annular groove and engaging said valve when the latter is in its closed position.

9. In a blasting cartridge, a casing having a chamber for receiving a charge of blasting pressure, a valve controlled by the pressure in said chamber and movable inwardly for releasing the pressure from said chamber, a valve seat facing inwardly toward said chamber and with which said valve engages, an annular groove formed in the walls of said seat, a rubber ring mounted in said annular groove and engaging said valve when the latter is in its closed position, and a stop shoulder outwardly with respect to said chamber beyond said ring, said valve having a shoulder engageable with said stop shoulder when said valve is closed.

10. In a blasting cartridge, a casing having a chamber for receiving a charge of gas at a blasting pressure, a valve controlled by the pressure in said chamber and movable inwardly for controlling release of the gas, a valve seat facing inwardly toward said chamber and having a surface whose trace on an axial plane makes an angle with the axis of the seat, said valve having a surface mating with said valve seat surface, spaced surfaces on the seat and valve respectively inclined relative to the first mentioned surfaces, and a resilient packing ring carried by the seat and engaging the last mentioned surface on the valve.

11. In a blasting cartridge, a casing for receiving a charge of gas at a blasting pressure said casing having a discharge opening sur-

rounded by a valve seat, a valve cooperating in the said seat, and a piston controlling said valve and having a spring-pressed, combined packing and check valve at its outer edge.

12. In a blasting cartridge, a casing having a chamber for receiving a blasting charge, a valve for releasing the charge from said chamber therein, a piston actuated by the pressure in said chamber for actuating said valve, a connection between said piston and said valve for permitting relative movement of said valve and piston, and stop means for limiting relative movement between said valve and piston.

13. In a blasting cartridge, a casing having a chamber for receiving a charge of blasting pressure, a valve for releasing said pressure from said chamber, and means controlled by the pressure in said chamber for actuating said valve comprising a rod secured to said valve, a piston, and a yielding connection between said piston and rod, and sealing means associated with said yielding connection for preventing leakage of pressure from said chamber past said rod.

14. In a blasting cartridge, a casing having a chamber for receiving a charge of blasting pressure, a valve for releasing said pressure from said chamber, and means controlled by the pressure in said chamber for actuating said valve comprising a rod secured to said valve, and a piston for actuating said rod, said rod and piston being relatively movable, and a seal carried by said piston for sealingly engaging the rod periphery for preventing leakage from said chamber past said rod.

15. In a blasting cartridge, a casing having a chamber for receiving a charge of blasting pressure, a valve for releasing said pressure from said chamber, and means controlled by the pressure in said chamber for actuating said valve comprising a rod secured to said valve and having an abutment at its outer end, a piston for actuating said rod and having a packed opening through which said rod extends, and a spring interposed between said rod abutment and said piston.

16. In a blasting cartridge, a casing having a chamber for receiving a blasting charge, a valve for releasing the pressure from said chamber, and means for effecting sudden actuation of said valve, said means including an element movable relative to the valve by the pressure in said chamber and a compressible spring interposed in the connection between the element and the valve for transmitting the pressure of the charge from the element to the valve.

17. In a blasting cartridge, a casing having a chamber for receiving a blasting charge, a valve for releasing the pressure from said chamber, and means for effecting sudden actuation of said valve, said means including a resilient member operatively connected to said valve and adapted to be distorted to store valve actuating energy, and a device actuated by the pressure in said chamber for distorting said member.

18. In a blasting cartridge, a casing having a chamber for receiving a blasting charge, a valve for releasing the pressure from said chamber, a rod connected to said valve, a piston loose on said rod, means connecting the piston to said rod, and common means for packing both the piston and the rod and the piston and the surrounding casing wall.

19. In a blasting cartridge, a casing having a chamber for receiving a blasting charge, a valve for releasing the pressure from said chamber,

a rod connected to said valve, a valve actuating piston movably mounted on said rod, and single means for packing between the rod, the piston and the surrounding casing wall.

5. 20. In a blasting cartridge, a casing having a chamber for receiving a blasting charge, a valve for releasing the pressure from said chamber, a

rod operatively connected to said valve, a valve actuating piston movably mounted on said rod and single means for packing between the rod, the piston and the surrounding casing wall and for serving as a check valve for the pressure supplied to said chamber.

WADE H. WINEMAN.
